UNITED STATES PATENT OFFICE.

WILLIAM WALLACE KEMP AND WILLIAM H. VAN HORN, OF BALTIMORE, MARYLAND.

HEATER FOR WATER-TUBE BOILERS.

1,234,173.

Specification of Letters Patent. Patented July 24, 1917.

Application filed November 11, 1915. Serial No. 60,853.

To all whom it may concern:

Be it known that we, WILLIAM W. KEMP and WILLIAM H. VAN HORN, citizens of the United States, residing at Baltimore, in the county of Baltimore City and State of Maryland, have invented new and useful Improvements in Heaters for Water-Tube Boilers, of which the following is a specification.

10 This invention relates to an improved water boiler and a heater or burner therefor.

The invention has among its objects to provide a water tube boiler of such peculiar construction that an explosive mixture may be confined in a small space therein and be thoroughly and completely consumed; to increase the general efficiency of the boiler; to provide a greater evaporative surface; to considerably reduce the formation of scale; to apply and confine the heat to the most advantageous point to prevent the loss of heat units; to effect the consumption of the fuel of the burner completely and without odor; to dispense with stacks and consequent loss of heat through them; to dispense with the furnace or fire box; to dispense with the opening through which atmospheric air is admitted to support combustion; and to provide a relatively small and compact structure.

It is a further object of the invention to provide my device with a burner which is detachable from the remainder of the apparatus in such manner that it may be easily removed when it is desired to renew the same, or when repair or cleaning thereof is necessary. Gas may be supplied to either end of the burner, so that in event of one of the valves being inadequate to supply sufficient fuel, the other valve may be operated, so that fuel is supplied by both of said valves.

It is a further object of the invention to provide a burner of such peculiar construction that it may be mounted in one of the water tubes of the boiler in such a manner that the water tube acts as a water jacket for the burner to not only protect the burner and its parts but to also provide for an increased evaporative surface heated by the reflected heat of combustion; wherein combustion may be forced to greatly increase the efficiency of the evaporative surface; and a burner by the use of which substantially perfect combustion of the fuel is had.

The above and other objects and advantages of this invention will be more clearly brought out in the following detail description of the present preferred embodiment of 60 the invention, the same being shown in the accompanying drawings wherein,

Figure 1 is a longitudinal vertical section taken centrally through the water tube boiler and the burner mounted therein. 65

Fig. 2 is a transverse section through the forward end of the water tube boiler taken on the line 2—2, Fig. 1.

Fig. 3 is a transverse section taken on line 3—3, Fig. 1. 70

Referring to the drawings which disclose one embodiment of our improved water-tube boiler, 10 designates the body portion of the furnace on which is mounted a steam drum 11 having water legs or headers 12 75 and 13 which extend downwardly from the front and rear ends respectively of the steam drum 11. Within the body section 10, and extending between the legs or headers, are a plurality of the water tubes 14 and a 80 burner 15 located centrally of the water tubes. About the sides of the body portion 10 and the steam drum 11 is a body wall or brick-work 16.

The body portion 10 of the furnace, which 85 may be constructed of any suitable refractory substance, has a combustion chamber 16' extending longitudinally through the same, the chamber having in its walls semi-cylindrical pockets 17 and substantially at 90 the longitudinal centers of these pockets are located the water tubes 14, an annular passage being provided thereby about the tubes for the products of combustion to insure the heating of the entire surface of the tubes. 95

The water tubes 14 extend between the headers 12 and 13 and communicate therewith, as shown in Fig. 1. Located centrally of the water tubes is the burner 15 which comprises an inner or burner tube 18 having 100 a plurality of burner tips 19 radiating from the sides thereof, and a water tube 20 arranged concentrically about the burner tube 18 and through which the burner tips 19 protrude, the space between the tubes 18 105 and 20 serving as a water jacket for the burner.

The burner 15 extends through central openings in the front and rear headers 12 and 13, the headers being provided with 110 sleeves 21 which fit about the burner, sufficient clearance, however being provided

between the burner and the sleeves to permit the burner to be removed from the furnace.

The burner tube 18 receives an explosive mixture, preferably a mixture of air and gas through suitable supply pipes 22, one of said pipes being attached to each of the ends of the burner tube 18, the flow of mixture being regulated by suitable valves 23. It will be noted that the burner tube is provided at both ends with connections for the admission of the explosive mixture, so that in event one of the pipes 22 is inadequate to supply sufficient fuel to the furnace, the valve in the other supply pipe may be operated to admit air and gas, and thus the supply of fuel may be substantially doubled. The water-space between the burner tube 18 and the water tube 20 is in communication with the headers at either end of the furnace by means of pipes or connections 24 which are located on the outside of the furnace, so that access thereto may be readily had. To start the furnace by igniting the gas as it issues from the burner, ports 25 are provided, which extend from the exterior of the furnace into the combustion chamber in which the water tubes and burner are located, and these ports 25 are adapted to be closed by suitable plugs 26.

The burner 15 is so disposed within the body section of the furnace, that the burner tips 19 project the flame, not directly against the water tubes 14, but against the walls of the semi-circular pockets 17 and between these tubes. The water tubes 14 are heated by the heat reflected from these walls, and, therefore, as direct heating of the tubes is partially eliminated, the liability of burning out the water tubes is materially decreased, while, at the same time, practically all of the heat units evolved by the combustion of the fuel are utilized in heating the water within the tubes.

As shown in the drawings, the combustion chamber 16', and the tubes 14 and burner 15 located therein are inclined upwardly and forwardly; the forward end of the body portion is cut-away as at 27, so that a relatively small passage is provided, and the products of combustion are caused to pass through this opening into the space provided around the steam drum 11. By so inclining the water tubes and the combustion chamber in the manner described, air pockets are avoided, and the accumulation of the products of combustion in the corners of the chamber is prevented. A better circulation of water within the tubes is provided, the path of circulation of the water being through the tubes 14, the headers 12 and 13 and the steam drum 11. Furthermore, the mud and other sediment which accumulates in the steam drum and the water tubes, and which is contained in the

water passing through the boiler is caused to drop or collect in the rear leg 13. In the bottom of this leg or header is provided a blow-off valve 28.

By providing the burner with a water jacket in the manner described, the water in the steam drum 11 and the water tubes 14 circulates continuously through the water space between the tubes 18 and 20 and through the connections 24, so that the burner tube 18 is effectually protected from heat evolved by the combustion of the fuel within the confined chamber of the furnace, and at the same time the evaporative surface of the boiler is materially increased.

When it is desired to remove the burner from the confined chamber of the furnace, the branch connections 24 connecting the burner to the headers are disconnected, and the burner may be removed from the furnace by withdrawing the same through either of the sleeves 21. Thus the burner may be easily removed for renewal, or when it is desired to clean or repair the same.

With the equipment described, granular refractory material is not required, in order to burn an explosive mixture, and such mixtures can be burned throughout the length of the confined chamber with complete combustion, even distribution of heat and with splendid temperature control. The water tubes 14 and the water space about the burner 15 are confined within a relatively small combustion chamber in which the explosive mixture is thoroughly and completely consumed and the heat units evolved in the combustion of the fuel are utilized in heating the water within the water tubes. The burner is adapted to receive atmospheric air through the connections described, and all other openings for the admission of atmospheric air to support combustion within the combustion chamber is dispensed with; that is to say, the explosive mixture is self-sustaining.

The steam drum 11 is mounted upon the top of the body portion 10 and is substantially inclosed by a brick-wall 16, the brick wall being so constructed as to form an annular or arcuate chamber 29 about the steam drum, which annular chamber is in communication with the chamber 16' by means of the hereinbefore described passage 27. Extending from the front of the furnace, but terminating at a point short of the rear wall thereof and located substantially on the level with the water in the steam drum is a horizontal baffle 30 which causes the products of combustion issuing through the passage 27 to travel backward substantially throughout the entire length of the steam drum and then forwardly before passing into the atmosphere. The steam drum and the annular passage thereabout are inclined upwardly and forwardly, so that air pockets in the

chamber 29 and steam pockets in the steam drum 11 are avoided, and the mud and other sediment which precipitates from the water admitted into the steam drum collects in the 5 rear leg or header 13.

Arising from the top of the furnace is a brick dome 31 lined with a metal sleeve 32, and provided with a damper or cover 33. Within the dome is located a water-feed 10 heater comprising a coil 34, to which coil is connected a pipe 35 leading from a suitable supply of water. Within the steam drum is located a mud drum 36 connected at one end to the coil 34 by means of a pipe 37. 15 The mud drum is inclined as shown, and at the lower rear end of the same is provided a pipe with a blow-off valve 38 for withdrawing the mud from within the mud drum. The mud drum is in communication 20 with the steam drum by means of an opening provided in the spout 39.

It will be noted that the heat evolved by the combustion of the fuel is utilized to heat successively the water tubes 14 and 20, steam 25 drum 11, and the coil 34, so that the heat of the products of combustion is thoroughly exhausted, and the efficiency of the furnace is thereby greatly increased.

The steam drum 11 is provided at its forward 30 end with a steam outlet 40, through which the steam generated in the water tubes and the steam drum passes to the usual steam pipes. Immediately below the steam outlet is provided a deflecting plate 41, and between the deflecting plate and the outlet opening 40 is a perforated pan 42, the deflecting plate and pan being provided to prevent priming and the passage of water up through the steam pipes. 43 designates the 40 usual water-gage.

To support the forward end of the drum 11 and relieve the front leg 12 of excessive pressure, an I-beam 44 is strung between suitable supports (not shown) to which I-beam, the steam drum 11 is connected by 45 means of the lug or projection 45. If desired, a plate 46 through which the supply pipe 22 to the burner extends, may be provided at the forward end of the furnace, so 50 as to improve its appearance. 47 designates the usual safety or blow-off valve.

Although the present disclosure sets forth the use of but a single burner in one of the water tubes of the boiler, it is to be understood 55 that it is within the spirit of this in-

vention to supply the water tubes with any desired number of burners, and that any number of steam drums may be used, and a number of boilers, if desired, may be connected in batteries, each boiler discharging 60 into a common steam drum or header.

What we claim is,—

1. A heater comprising a drum having a group of water tubes therebeneath, a wall inclosing the tubes and providing a substantially closed chamber about the tubes, the wall so shaped as to form substantially semi-circular pockets behind each tube, and burners within the inclosing wall so placed that the direct heat of the flame avoids the tubes 65 and is reflected on said tubes by the semi-circular pockets.

2. A heater comprising a drum having a group of water tubes therebeneath, a wall inclosing the tubes and providing a substantially closed chamber about the tubes, a wall so shaped as to form substantially semi-circular pockets behind each tube and burners within the inclosing wall located so that the direct heat of the flame strikes the line 75 of jointure of the semi-circular pockets and is reflected on the tubes by said pockets.

3. In combination, a substantially closed chamber having in its walls semi-circular pockets, water tubes in said pockets, and a 85 burner located centrally of said tubes and projecting the flame against the walls of said pockets to heat said tubes by the heat reflected from said walls.

4. In a water tube boiler, a drum having 90 a group of water tubes therebeneath, a combustion chamber about said tubes, means in said chamber for heating the water in said tubes, a chamber about said drum, a passage adjacent one end of the drum whereby 95 said combustion chamber and said chamber about said drum communicate, a baffle extending longitudinally of said drum and terminating short of the end of said drum opposite said passage to cause the products 100 of combustion from said combustion chamber to pass lengthwise of said drum.

In testimony whereof we have hereunto set our hands in presence of two subscribing witnesses.
